UNITED STATES PATENT OFFICE.

JOHN F. LESLIE, OF MADISON, WISCONSIN.

SEAM FOR METAL RECEPTACLES.

1,170,288.

Specification of Letters Patent.

Patented Feb. 1, 1916.

Application filed February 11, 1915. Serial No. 7,626.

To all whom it may concern:

Be it known that I, JOHN F. LESLIE, a citizen of the United States, residing at Madison, in the county of Dane and State 5 of Wisconsin, have invented a new and useful Seam for Metal Receptacles, of which the following is a specification.

This invention relates to seams for metal receptacles such as tanks, cans, pails, and the 10 like, one of the objects of the invention being to provide a simple and efficient means for attaching the top or bottom of a tank or other receptacle to the metal wall thereof, it being possible to get a water-proof joint 15 without the use of solder such as heretofore required.

With the foregoing and other objects in view which will appear as the description 20 proceeds, the invention resides in the combination and arrangement of parts and in the details of construction hereinafter described and claimed, it being understood that changes in the precise embodiment of the invention herein disclosed can be made with- 25 in the scope of what is claimed without departing from the spirit of the invention.

In the accompanying drawings, the preferred form of the invention has been shown.

In said drawings—Figure 1 is a horizontal 30 section through a portion of a can having the present improvements combined therewith. Fig. 2 is an enlarged section on line A—B Fig. 1. Fig. 3 is a perspective view of portions of the joint separated.

Referring to the figures by characters of 35 reference, 1 designates the sheet metal wall of a receptacle, the same being provided with an outstanding flange 2 formed with concentric corrugations 3. Said flange merges 40 at its outer edge into a flat ring-like base 4 which extends inwardly beyond the wall 1 and is bent upwardly and outwardly to provide a rib 5. From this rib extends a flange 6 which is depressed relative to the top of 45 the rib and is formed with radial corrugations 7. The flange 6 rests upon the base ring 4 and the corrugated portion thereof is adapted to support the depressed marginal portion 8 of the plate 9 constituting the top 50 or bottom of the receptacle. The annular shoulder 10 formed by depressing the marginal portion 8 is adapted to engage the annular shoulder 11 formed by depressing the flange 6 so that when the depressed portion 55 8 is bearing on the corrugations 7, the shoulder 10 will bear inwardly against the shoul-

der 11, as shown in Fig. 2. Bearing on and supported by the annular portion 8 of the plate 9 is a washer or gasket 12 formed of fiber or any other suitable material and this 60 gasket is adapted to be contacted by the annular corrugations 3 on the flange 2. Thus it will be seen that by inserting rivets through the flanges 2 and 6, the base ring 4 and the gasket 12, the various parts can be 65 clamped tightly together, the corrugations 3 all biting into the gasket while the corrugated flange 6 provides a yielding support for the depressed portion 8 of the plate 9. Thus positive sealing of the joint is insured 70 as an air and water tight connection is provided at each point of contact between the corrugations 3 and the gasket 12. The rivets have been indicated at 13.

It is to be understood that the gasket 12 75 can be made of any desirable material capable of yielding under the binding action of the corrugations thereagainst.

What is claimed is:

1. A seam for metal receptacles, including 80 a base ring having an annular upstanding bead, an annular flange extending from the bead and having radial corrugations bearing on the base ring, a plate bearing upon the bead and having a depressed marginal portion bearing upon the corrugated flange, a flange integral with the outer edge of the base ring and having an annular corrugation, said last named flange overhanging the depressed marginal portion of the plate, a 85 gasket interposed between said depressed marginal portion and the last named corrugated flange, and means extending through the flanges, gasket, depressed marginal portion and base ring for binding the parts 90 together.

2. A seam for metal receptacles, including 95 a base ring having an upstanding bead at its inner edge, a flange extending outwardly from the bead and having radial corrugations constituting a yieldable support for engaging the base ring, a plate having a marginal depressed portion bearing upon the said corrugated flange, a corrugated flange integral with the outer edge portion 100 of the base ring, the said corrugations being extended annularly and overhanging the depressed marginal portion of the plate, and a gasket interposed between and clamped by 105 said depressed marginal portion and the last named corrugated flange.

3. A seam for metal receptacles including

upper and lower yieldable members, a plate extending therebetween and resting upon one of the members, a gasket supported by the plate and contacted by the other yieldable member, means extending through the plate, members and gasket for binding them together, each of said yieldable members being corrugated, the corrugations of one of the members being disposed substantially at

right angles to the corrugations of the other member.

In testimony that I claim the foregoing as my own, I have hereto affixed my signature in the presence of two witnesses.

JOHN F. LESLIE.

Witnesses:

R. N. NELSON,
H. H. BUSHNELL.
